EXPANSIBLE DRUM

George E. Kentis, Jr., Fairview Village, Ohio, assignor to The Yoder Company, Cleveland, Ohio, a corporation of Ohio

Application August 4, 1945, Serial No. 608,913

17 Claims. (Cl. 242—72)

1

This invention relates to a coiling and uncoiling mechanism for sheet material, more particularly a sectional drum on which sheet metal which is to be coiled for handling, uncoiled for processing (surface treating, heating, normalizing, edging, slitting or shaping) or recoiled after being processed or operated upon ready for cutting into lengths or for fabrication.

One object of the invention is to provide an improved drum of this type consisting of a plurality of movable sections supported for movement radially outwardly and inwardly and means for substantially simultaneously operating the sections, whereby the drum may be expanded or contracted.

In all drums of this type, of which I have knowledge, one or more sections thereof were fixed to a supporting shaft or rod, so that only a portion of the drum was operated radially in either direction. In some constructions of this form the expanding and contracting means operated on one movable drum section which in turn controlled or actuated the remaining movable section or sections of the drum. In this form of construction difficulty resulted in so positioning the sections when expanded, that they and the fixed drum section formed a true circle and/or in preventing one of the movable sections from yielding inwardly due to the pressure of the material thereon during coiling or winding thereof. Where a non-circular condition existed for any reason, one edge of one movable section would be off-set relative to the adjacent edge of the adjoining movable section, the effect of which formed a distorted portion in the first and succeeding convolutions of the material as coiling took place. To eliminate the difficulty above referred to, another object of the invention is to provide an improved drum all sections of which are expansible and contractable, having means for substantially simultaneously operating all the sections radially outwardly a predetermined distance.

Another object of the invention is to provide an improved drum of this type consisting of movable sections wherein the supports and operating means therefor are materially simplified and readily assembled.

Another object of the invention is to provide in a drum of this type consisting of a rotatable shaft and movable drum sections, improved means for supporting and guiding the sections during their movement to and from their expanded position.

Another object of the invention is to provide an improved drum consisting of radially movable

2

sections and operating means therefor arranged to rigidly support the sections when in expanded position to resist inward movement thereof.

A further object of the invention is to provide, in a drum of this type, improved means for securing or clamping the end of the sheet material to the drum.

Other objects of the invention will be apparent to those skilled in the art to which my invention relates from the following description taken in connection with the accompanying drawings, wherein

Fig. 1 is a longitudinal section showing a drum embodying my invention, taken on the line 1—1 of Fig. 2.

Fig. 1a is a sectional view showing the drive mechanism for the shaft and fluid operated mechanism.

Fig. 2 is a section partly on the line 2—2, partly on the line 2a—2a of Fig. 1.

Fig. 3 is a fragmentary end elevation of the drum showing the clamping means for the end portion of the material.

Fig. 4 is a fragmentary section on the line 2a—2a of Fig. 1, but showing the position of the clamping parts when clamping the material to the shaft.

Fig. 4a is an enlarged view of the clamp.

Fig. 5 is a fragmentary section on the line 5—5 of Figs. 2 and 4 (enlarged).

Fig. 5a is a fragmentary section substantially on the line 5a—5a of Fig. 3 (enlarged).

Fig. 6 is a fragmentary longitudinal section of the drum showing the drum sections thereof in expanded position on the line 6—6 of Fig. 7.

Fig. 7 is a section partly on the line 7—7 and partly on the line 7a—7a of Fig. 6.

Fig. 8 is a view similar to Fig. 1 but showing a modified form of construction, taken on the line 8—8 of Fig. 10, and showing the drum sections in contracted position.

Fig. 9 is a view similar to Fig. 8 but showing the drum sections expanded.

Fig. 10 is a section on the line 10—10 of Fig. 8.

Fig. 11 is a section on the line 11—11 of Fig. 9.

In the drawings 1 indicates a shaft supported in suitable bearings 2, 2x, which are provided on supports 2a, 2x', respectively. The shaft carries on its outer end portion (the portion outwardly of the bearings) a drum, indicated as an entirety at 3, consisting of a plurality of sections 3a all of which are movable radially of the axis of the shaft 1, as later set forth. The drive means for the shaft 1 preferably consists of a gear keyed thereto and disposed between the sup-

ports 2a, 2x', and in mesh with a pinion 1x', which is fixed to a drive shaft 1z. The shaft 1 is hollow to accommodate a reciprocatable thrust member 4, the operation of which serves to operate the drum sections outwardly radially and control their movement in the opposite direction. The outer end portion of the member 4 is reduced to provide a shoulder 4a for a purpose later set forth. Any suitable means may be employed for operating the thrust member 4; for example, hydraulically operated means later referred to.

I preferably provide four drum sections 3a, the outer surfaces of which are curved on a predetermined radius to provide a true cylinder (except for the spacing between the sections when expanded) when they are in expanded position. Each of the sections 3a is movably connected to the drum shaft in the following manner: 5 indicates a guide member carried by the shaft 1 and 5b indicates a recess formed in the inner wall of the adjacent drum section, the side walls of the recess slidably fitting the opposite sides of the guide member 5. Each of the guide elements 5 is fixedly mounted in a recess 5a formed in the shaft 1. The guide elements 5 and recesses 5b therefor are elongated longitudinally of the shaft 1 so as to provide adequate bearing surfaces therebetween. 5' indicates as an entirety spring operated means which yieldingly connect each section 3a to the shaft and operate to normally maintain it in contracted position and in assembled relation thereto and the other drum sections 3a. The connecting means 5' for each section consist of spaced sets of devices 6 disposed adjacent the opposite ends of the section, whereas the connecting and guiding members 5 are disposed between and in line with the sets of devices 6.

As later set forth, the sets of devices 6 for each section 3a are arranged to limit the expanding or radial outward movement thereof, to prevent disengagement of the guide element 5 from the side walls of the recess 5b when the drum section is in its expanded position (see Fig. 7).

Each set of devices 6 for each drum section consists of the following: 6a indicates a recess formed in the outer surface of the shaft 1 and preferably having a circular side wall. For reasons later apparent, the axis of the recess 6a is disposed on a radius midway the opposite side edges of the adjacent drum section. 7 indicates a supporting element mounted in the shaft 1 and extending radially of its axis outwardly axially of the recess 6a. The element 7 preferably consists of a screw threaded at its inner end into an inwardly extending threaded opening 7a formed in the bottom wall of the recess 6a and extending outwardly therefrom into a through opening 8 formed in the adjacent drum section 3a. The screw 7 is of a length to terminate at its outer end inwardly of the outer surface of the drum section 3a when the latter is in contracted position (see Figs. 1 and 2). The outer portion of the opening 8 is enlarged to form an annular shoulder 8a. 9 indicates an annular member surrounding the screw 7 and adapted to be seated in the recess 6a when the adjacent drum section is in contracted position, as shown in Fig. 1. The annular member 9 is provided at its outer end with a laterally extending flange 9a which engages the shoulder 8a. The inner end of the member 9 is provided with an inwardly extending flange 9b which slidably engages the screw 7. A spring 10 is coiled around the

screw 7 and interposed between a collar or head on its outer end and the flange 9b and normally tends to move the annular member 9 inwardly and the drum section 3a therewith through the engagement of the flange 9a with the shoulder 8a.

When the drum sections 3a are expanded outwardly by a mechanism indicated as an entirety at 11, the annular members 9 move therewith, due to the engagement of the shoulders 8a with the flanges 9a, the annular members being guided in this movement by their engagement with the screws 7 and side walls of the recesses 6a (see Figs. 6 and 7). In this form of construction the springs 10 co-act with the screws 7 and the annular members 9 to yieldingly maintain all of the sections in contracted position, but permit expansion of the drum sections, as later set forth. As will be observed from Figs. 6 and 7, when the drum sections 3a are expanded, the springs 10 are compressed between the heads of the screws 7 and flange 9b and accordingly operate to limit the expansion or outward movement of the drum sections; also, due to the fact that the annular members 9 of the devices 6 for each drum section 3a engage the walls of the recess 6a and opening 8, the drum section is held against endwise movement.

The operating mechanism 11 for expanding the drum sections 3a and releasing them for movement under the influence of the springs 10 consist of a set of co-acting elements 11a between the shaft 1 and each drum section and an operating member or head 12 rotatably mounted on the outer end of the thrust member 4 for simultaneously operating the movable elements of the sets of elements 11a for all of the drum sections. I preferably provide two sets of elements 11a for each drum section 3a disposed at opposite sides of and equal distances from the adjacent guiding and connecting members 5 and spring operated means 5', whereby non-radial forces or stresses thereon are eliminated and radial movement of the drum sections result. Each set of co-acting elements 11a for each drum section 3a consists of a bar 13 slidably fitting an elongated recess 14 formed in the shaft 1 and extending longitudinally thereof (that is, from a point adjacent the bearing 2 outwardly) and a bar 13' fixedly seated in an elongated recess 13'' formed in and extending longitudinally of the inner wall of the adjacent drum section 3a, preferably from end to end thereof. The bar 13' may be secured in its seat 13'' by a plurality of counter-sunk cap screws 13x. The outer end of the bar 13 is rigidly connected to the operating member 12 by cap screws 12a. The bar 13 is provided on its outer side with spaced cams 15 each consisting of an inclined wall 15a and a contiguous dwell wall 15b, whereas the inner side of the bar 13' is provided with spaced cams 15' each consisting of an inclined wall 15a' and a contiguous dwell wall 15b', these walls 15a, 15a', 15b, 15b', being reversely related with respect to the walls 15a, 15b, to provide for the co-action therebetween. By preference, the bar 13' is cut away as shown at 16, to accommodate the cams 15 on each bar 13 when the adjacent drum section 3a is in retracted position. In this form of construction one end wall of each cutaway 16 serves as one of the inclined walls 15a' and the outer surface of the bar contiguous thereto serves as the adjacent dwell wall 15b'. By providing co-acting inclined walls 15a, 15a', on both bars 13, 13', a relatively short initial movement of the bars 13 will serve to expand the drum sections the desired distance and permit a

relatively long movement thereof, with the dwell walls 15b, 15b', in engagement, so that the drum sections, when in expanded position, will have adequate support to resist inward stresses due to coiling of the material thereon.

The inner wall of the shaft 1 adjacent its outer end is recessed to accommodate a bushing 17 in which the thrust member 4 is slidably mounted. The shoulder 4a provided on the thrust member 4 adjacent its outer end the member forms a seat for an inner sealing ring 18. An anti-friction bearing 19 is mounted between the ring 18 and an outer seal ring 20 and seated in an annular recess 21 formed in the member 12. A nut 22 threaded on the outer end of the member 4 engages the seal ring 20, whereas an annular plate 23 secured to the member 12 by cap screws 23a engages the bearing 19 to secure it in the member 12. 24 indicates a cap-removably secured to the member 12 by cap screws 24a.

25 indicates as an entirety devices for removably clamping the end portion of the sheet material to the shaft 1 when it is to be coiled on the drum sections 3a. The devices 25 are mounted in an open sided box or housing 26 the bottom wall 26' of which is secured by counter-sunk cap screws 26a to the outer wall of the shaft 1. The box 26 is mounted between two of the drum sections 3a and extends longitudinally of the shaft 1 from a point adjacent its bearings 2 to the outer end thereof, the side walls of the adjacent drum sections being cutaway from end to end to accommodate the box. The clamping devices 25 consist of a pair of related members 27, 27a, movably mounted in the box 26 and relatively movable to engage and disengage the sheet material A. The members 27, 27a, are preferably formed of a plurality of endwise related sections 27', 27'', respectively (see Figs. 5 and 5a), so as to compensate for any unevenness in the sheet material A when the latter is clamped. The sections 27'' are formed with through openings 28 in each of which is mounted a screw 28a threaded into the bottom wall 26'. The outer portion of each opening 28 is enlarged to accommodate a spring 29 which surrounds the adjacent screw 28a and is interposed between the head of the latter and the bottom wall of the enlarged portion of the opening 28. The springs 29 operate normally to move the sections 27'' inwardly. The outer sides of the clamping sections 27'' are provided with longitudinally extending aligned ribs 30 which slidably engage the bottom wall of a recess 30a formed in the adjacent side wall of the box 26 (see Fig. 4), to cooperate with the screws 28a to guide the sections 27'' inwardly under the influence of the springs 29 and outwardly due to the operation of co-acting cams 31, 31a (later referred to). The inner sides of the sections 27'', at their inner ends are provided with projecting ledges 32 on which the sections 27' forming the clamping member 27 may slide toward and from the sections 27'' during movement of the latter. The outer side of each clamping section 27' is formed with a longitudinally extending recess 33, the bottom wall of which is shaped to provide the cams 31. 34 indicates a thrust device disposed between the clamping sections 27' and the adjacent side wall of the box 26 and provided on its inner side with the cams 31a, each arranged to co-act with one of the cams 31. As shown in Figs. 2 and 4, the side wall of the box 26 is formed with a longitudinally extending recess 26x, the walls of which guide the thrust

device 34 endwise inwardly and outwardly, whereas the side walls of the recesses 33 overlap the sides of the thrust device 34, whereby the latter prevents dislocation of the clamping sections 27' when in normal or non-clamping position, but are spaced sufficiently to permit movement of these sections when operated to and from their clamping position. The outer end of the thrust device 34 is secured by screws 34a to a lug 35, which is preferably formed integrally on the side wall of the operating member 12 (see Fig. 3), whereby the thrust device 34 moves with the latter in either direction. Accordingly, when the operating member 12 is operated outwardly by the thrust member 4 to expand the drum sections 3a, the cams 31, 31a, will co-act to move the sections 27' toward the clamping member 27a. When the clamping members 27, 27a, are in normal position (that is, the drum sections 3a are in retracted position (see Fig. 1) and the thrust device 34 is in the position shown in Fig. 5a) the member 27a is in engagement with the bottom wall 26a and the clamping elements 27' are spaced from the member 27a and form a throat to receive the end portion of the sheet material, as shown in Fig. 2. Upon insertion of the sheet material in the throat, and operation of the operating member 12 outwardly to expand the drum sections 3a and movement of the thrust device 34 outwardly, the clamping sections 27' will be forced by the latter against the sheet material and the pressure will be exerted through the material against the clamping member 27a and move the latter outwardly in opposition to the tension of the springs 29, and thereby provide a yieldable clamping effect on the material between the clamping sections 27' and the clamping member 27a as shown in Fig. 4.

40 As shown in Figs. 2 and 4, the active faces of the clamping members 27, 27a, are disposed in planes tangential to imaginary circles concentric to the axis of the shaft 1 and movement of the member 27 is in a direction substantially at right angles to the active face of the member 27a, so that the pressure exerted on the latter, in clamping the material to the drum, is in an outward direction and results in moving the member 27a longitudinally of the screws 28a.

45 By spacing of the side walls of the recesses 33, formed in the clamping sections 27', the latter are free to move outwardly with the clamping member 27a in exerting pressure through the material thereto to effectively clamp the material. Following the clamping of the material to the drum, the latter may be rotated to coil the material thereon. Upon movement of the operating member 12 and thrust device 34 inwardly the clamping devices will disengage the material.

50 60 By spacing of the side walls of the recesses 33, formed in the clamping sections 27', the latter are free to move outwardly with the clamping member 27a in exerting pressure through the material thereto to effectively clamp the material. Following the clamping of the material to the drum, the latter may be rotated to coil the material thereon. Upon movement of the operating member 12 and thrust device 34 inwardly the clamping devices will disengage the material.

55 65 The form of construction shown in Figs. 1 to 7, inclusive, may be employed as an uncoiler of a coil of sheet material. In this employment, the drum sections 3a are first retracted, the coil is then positioned on the drum and the drum sections expanded to grip the coil, the clamping devices 25, although operated as above set forth, being inactive.

70 The hydraulically operated means for endwise moving the thrust member 4 consists of the following: 37 indicates a supplemental support hav-

7
ing a through opening $37a$ axially aligned with opening in the shaft 1 for the thrust member 4 . The supplemental support 37 is preferably mounted on a bracket (not shown) provided on the support $2x'$. The outer end of the supplemental support 37 is suitably secured to the inner head 38 of a cylinder $38a$. The thrust member 4 extends through the opening $37a$ into the cylinder 38 and is provided at its inner end with a piston 39 . The shaft 4 intermediate the opposite ends of the opening $37a$ is provided with a key 40 slidably fitting an elongated groove or way $37b$ formed in the inner wall of the opening $37a$, the engagement of the key 40 with the walls of the groove $37b$ serving to prevent rotation of the thrust member 4 . The endwise movement of the thrust member 4 is effected by supplying fluid (gas or oil) under pressure into the cylinder $38a$ to either side of the piston 39 and discharging the fluid from the cylinder at the opposite side of the piston. As shown cylinder heads $38, 38'$, are provided with ducts $41, 41a$, respectively, the inner ends of which terminate within the cylinder $38a$. The outer ends of the ducts $41, 41a$, are connected with fluid circulating pipes $42, 42a$, respectively. The pipes $42, 42a$, lead from a valve mechanism having connection with a pump and a reservoir (not shown), the valve mechanism being operable to selectively supply fluid under pressure through one pipe to one end of the cylinder $38a$ (dependent on the direction in which the thrust member is to be moved) and permit discharge of the fluid from the other end thereof for return through the adjacent pipe to the reservoir. The valve mechanism may be similar in construction to that shown in the Letters Patent No. 2,351,894 to E. W. Allardt.

Figs. 8 to 11, inclusive, illustrate a modified embodiment of my invention adapted to be employed specifically for uncoiling a coil of sheet material, for which reason clamping devices for the end portion of the material are omitted. The shaft $1'$ may be rotatably supported and driven in the manner already set forth. The drum sections $3a'$ are mounted on the shaft $1'$ by parts similar to that shown in Figs. 1, 2, 6 and 7 and by separate spring operated means $5x$, which are also similar to like parts shown in Figs. 1, 2, 6 and 7. The operating means $11'$ are likewise similar to like parts shown in these figures, except that the co-acting cams indicated at $15x, 15x'$ between the bars $13z$ and drum sections $3a'$, respectively, consist of relative long inclined co-acting surfaces, so that after a coil of material is positioned on the drum, the operating member 12 may be operated to move all of the bars $13z$ endwise; in the movement of the bars $13z$, the cams $15x$ thereon will co-act with the cams $15x'$ on the drum sections $3a'$ to expand the latter into engagement with the coil under pressure to rigidly secure it thereto, as will be understood from Fig. 9. In this form of construction, the thrust member $4'$ and operating member $12'$ are moved outwardly to permit retraction of the drum sections $3a'$ under the influence of the springs $10'$ (see Figs. 8 and 10) and moved inwardly to expand the drum sections $3a'$ (see Figs. 9 and 11) as above set forth.

36 indicates an annular wall fixed to the shaft $1'$ inwardly of the drum sections $3a'$ to form a stop for the coil when positioned thereon.

To those skilled in the art to which my invention relates, many changes in construction and widely differing embodiments and applica-

tions of the invention will be apparent without departing from the spirit and scope thereof. My disclosures and the description herein are purely illustrative and not intended to be in any sense limiting.

What I claim is:

1. In apparatus of the class described, the combination with a shaft and supporting means for one end of said shaft, of a plurality of arcuate sections surrounding said shaft outwardly of said supporting means therefor and related to form a drum, radially extending guide means between said shaft and each drum section for guiding the latter radially and consisting of a recess formed in one part and a device on the other part slidably fitting said recess, connections between said shaft and each drum section intermediate the ends thereof for movably connecting it thereto and prevent endwise movement of the section relative to said shaft, and means between said shaft and said drum sections and movable independently of said shaft for moving the sections outwardly.

2. An apparatus as claimed in claim 1 wherein the connections for each drum section include a spring operated member and the spring therefor is put under tension when the drum section is moved outwardly.

3. An apparatus as claimed in claim 1 wherein the radially extending guide means consist of an elongated recess formed in each drum section and an elongated bar for each recess fixed to said shaft and the connections between each section and said shaft are disposed in line with and at opposite ends of the adjacent elongated bar.

4. An apparatus as claimed in claim 1 wherein the means for moving the drum sections outwardly consists of sets of co-acting endwise relatively movable elements, a head fixed to the movable elements, power mechanism associated with said shaft supporting means and connections extending through and movable relative to said shaft between said mechanism and said head for operating the latter.

5. An apparatus as claimed in claim 1 wherein the means for moving the drum sections outwardly consist of co-acting elements carried by said shaft and each drum section, a head connected to the elements carried by said shaft, and means for reciprocating said head in a direction longitudinally of said shaft.

6. In apparatus of the class described, the combination with a support, of a hollow shaft rotatably mounted at one end of said support, means for rotating said shaft, a plurality of arcuate sections related to form a drum and movable radially relative to said shaft, connections between each said section and said shaft for supporting it thereon and arranged to guide said section radially when moved, means for moving said drum sections radially outwardly, said moving means consisting of a set of co-acting elements between and carried by each drum section and said shaft, a thrust member extending through said hollow shaft, power means connected to the inner end of said thrust member for reciprocating it, a head carried by the outer end of said thrust member and connected to the co-acting elements carried by said shaft, and means for moving said drum sections radially inwardly.

7. An apparatus as claimed in claim 6 wherein the head is rotatably mounted on the outer end of said thrust member.

8. In apparatus of the class described, the combination with a support, of a hollow shaft rotat-

ably mounted at one end of said support, means for rotating said shaft, a plurality of arcuate sections related to form a drum and movable radially relative to said shaft, connections between each said section and said shaft for supporting it thereon and arranged to guide said section radially when moved, means for moving said drum sections radially outwardly, said moving means consisting of sets of co-acting elements between and carried by each drum section and said shaft at opposite sides of the connections for said drum section, a thrust member extending through said hollow shaft, power means connected to the inner end of said thrust member for reciprocating it, a head carried by the outer end of said thrust member and connected to the co-acting elements carried by said shaft, and means for moving said drum sections radially inwardly.

9. In apparatus of the class described, the combination with a support, of a shaft rotatably mounted at one end in said support, means for rotating said shaft, a plurality of arcuate sections related to form a drum and movable radially relative to said shaft, means for moving said drum sections radially outwardly, longitudinally spaced spring operated means between said shaft and each drum section for connecting the latter to said shaft and for moving the section radially inwardly, and separate connections between said shaft and each said section intermediate of and in line with said spaced spring operated means for guiding said section radially when moved in either direction.

10. In apparatus of the class described, the combination with a support, of a shaft rotatably mounted at one end in said support, means for rotating said shaft, a drum on which sheet material may be coiled, consisting of a plurality of arcuate sections movably radially relative to said shaft, slidably related elements between said shaft and each said drum section for supporting the section on said shaft and arranged to guide the section radially when moved, means operable in one direction for moving said drum sections radially outwardly, means for moving said drum sections inwardly radially when the first-mentioned moving means are operated in the opposite direction, and means for clamping the end of the sheet material to said shaft, said clamping means consisting of a pair of relatively movable elements movably mounted in the side wall of the shaft between adjacent drum sections, and means actuated by said first mentioned moving means for moving said elements into engagement with the material.

11. An apparatus as claimed in claim 10 wherein in one of said clamping elements is normally held in non-clamping position by a spring which is put under tension when said elements are operated to clamp the material, whereby said spring moves said element to release the material when said first mentioned moving means are operated in the opposite direction.

12. In apparatus of the class described, the combination with a support, of a shaft rotatably mounted at one end in said support, means for rotating said shaft, a drum on which sheet material may be coiled, consisting of a plurality of arcuate sections, means between said shaft and each said drum section for supporting the section on said shaft for movement radially thereof and arranged to guide the section radially when moved, means operable in one direction for moving said drum sections radially outwardly, and means for clamping the end of the sheet material

to said shaft, said clamping means consisting of a housing fixed to and extending longitudinally of said shaft between adjacent drum sections, a clamping member mounted in said housing to slide outwardly and inwardly and arranged to engage one side of the sheet material, a spring engaging said member and normally tending to move it inwardly, a separate member mounted in said housing and movable toward and from said first mentioned member for engaging the opposite side of the sheet material, and means actuated by the movement of said moving means for moving said last mentioned member toward said first mentioned member and exert pressure thereon through the material to move the first mentioned element outwardly to put said spring under tension, whereby the material is resiliently clamped between said clamping members.

13. In apparatus of the class described, the combination with a support, of a shaft rotatably mounted at one end in said support, means for rotating said shaft, a drum on which sheet material may be coiled, consisting of a plurality of arcuate sections, means between said shaft and each said drum section for supporting the section on said shaft for movement radially thereof and arranged to guide the section radially when moved, means for moving said drum sections radially outwardly, said moving means including a set of coacting elements between said shaft and each said drum section and a head connected to the elements carried by said shaft for moving said elements longitudinally of said shaft, and means for clamping the end of the sheet material to said shaft, said clamping means consisting of a housing fixed to and extending longitudinally of said shaft between adjacent drum sections, a clamping member mounted in said housing to slide outwardly and inwardly and arranged to engage one side of the sheet material, a spring engaging said member and normally tending to move it inwardly, a separate member mounted in said housing and movable toward and from said first mentioned member for engaging the opposite side of the sheet material, a device mounted in said housing to move endwise therein, operating connections between said head and said device, and co-acting elements between said device and the last mentioned clamping member, for moving the latter toward said first mentioned clamping member and exert pressure thereon through the material to move the first mentioned member outwardly to put said spring under tension, whereby the material is resiliently clamped between said clamping members.

14. In apparatus of the class described, the combination with a support, of a shaft rotatably mounted at one end therein, a drum consisting of a plurality of arcuate sections movable radially outwardly and inwardly relative to said shaft, slidably related elements carried by said shaft and each drum section disposed midway between the longitudinal side edges of the latter arranged to guide the section radially, a plurality of members mounted in and projecting radially from said shaft, one for each drum section disposed in alignment with the adjacent slidably related elements for said drum section, a collar on the outer end of each projecting member, an annular member surrounding each projecting member and movably seated in the adjacent drum section for movement relative to said projecting member and provided at its inner end with an inwardly extending flange, a spring between each said collar and the adjacent flange and normally exerting

11

pressure on said flange to move the adjacent drum section inwardly radially, and means for moving said drum sections outwardly radially against the tension of said springs.

15. An apparatus as claimed in claim 14, where-
in the slidably related elements between said shaft and each of said sections consist of a longitudinally extending recess formed in the inner wall of the drum section and an elongated guide mem-
ber carried by said shaft and extending into said recess and having sliding engagement with the side walls thereof.

16. An apparatus as claimed in claim 14, where-
in the moving means for each drum section en-
gage therewith at opposite sides of the slidably
related elements for the drum section.

17. In apparatus for coiling sheet material, the
combination with a support, of a rotatable shaft
mounted at one end thereon, a drum having sec-
tions movably mounted on said shaft, means for
operating said movable sections, and means for
clamping the end of the material in fixed relation
to the drum, said clamping means consisting of
a box or housing fixed to and extending longi-
tudinally of said shaft, a clamping member for
engaging one side of the material, slidably mount-
ed in said box for movement outwardly and in-

wardly, a spring engaging said member and nor-
mally tending to move it inwardly, a separate
clamping member for engaging the opposite side
of the material, and means between said separate
clamping member and the adjacent wall of said
box for moving said member toward said first
mentioned clamping member to clamp the mate-
rial therewith and exert pressure through the
material and move said first mentioned member
outward in opposition to the tension of said
spring, whereby the material is yieldingly clamped
between said members.

GEORGE E. KENTIS, JR.
